TO DURHAM DUPLEX RAZOR COMPANY, OF NEW YORK, N. Y., A CORPORATION OF
NEW YORK.

GRINDING-MACHINE FOR RAZOR-BLADES.

1,075,228.

Specification of Letters Patent.

Patented Oct. 7, 1913.

Application filed June 30, 1910. Serial No. 569,772.

To all whom it may concern:

Be it known that we, THOMAS C. SHEEHAN and JOHN E. DREW, citizens of the United States, residing at Jersey City, in the county of Hudson and State of New Jersey, have invented a new and useful Improvement in Grinding-Machines for Razor-Blades, of which the following is a specification.

10 This invention relates to a machine for grinding razor blades, particularly thin replaceable blades of the type used with certain safety razors; and it has for its main object the production of a machine capable 15 of rapidly and accurately grinding successive blades so that the cutting edges of all will be exactly alike.

Another object is to provide a machine for grinding blades in oil, whereby fine and true edges are produced without danger of injury to the temper of the steel.

Still another object is to provide a machine in which a blade is automatically carried past and held against the grinder so 25 that the grinding operation is progressive from one end of the blade to the other and at all times uniform.

A further object is to provide a machine having a grinder including two separated 30 disks, the first disk coming into contact with an advancing blade serving to remove the major portion of the material necessary to form the edge, while the second disk operates to finish the grinding operation under 35 a lighter load and produce a smoother edge than is possible when only a single cut is made.

A further object is to provide a machine in which the ground edge is polished after 40 the grinding operation is completed.

With these and other objects not specifically mentioned in view, the invention consists in certain constructions and combinations which will be hereinafter fully described, and then specifically set forth in the claims hereunto appended.

In the accompanying drawings which form a part of this specification and in which like characters of reference indicate 50 the same parts, Figure 1 is a plan view of a machine constructed in accordance with the invention, Fig. 2 is a front elevation of the structure shown in Fig. 1, partly in section, Fig. 3 is a side elevation of the structure shown in Figs. 1 and 2, and Figs. 4 and

5 are detail views, upon an enlarged scale, of one of the polishing wheels shown in Figs. 1, 2 and 3.

In carrying the invention into effect, there is provided a grinder which may vary within wide limits. In the best constructions, however, a grinding wheel is used, and this wheel may be made of any suitable abrasive material. In the device selected to illustrate the invention, the grinding wheel includes two separated disks 1 and 2 past which a blade is carried during the grinding operation in a manner to be hereinafter described. These disks are fixed upon a shaft 3 journaled in a bracket 4 adjustably mounted upon a frame 5 which is the main frame of the machine. Upon one end of this shaft is fixed a pulley 6 over which a belt 7 runs. This belt derives its motion from a suitable line shaft over the machine and not shown. 75 It may be here remarked that in the device selected to illustrate the invention, there are two complete grinding wheels and two sets of blade forwarding devices. These wheels and devices are identical, and a detailed description of one is therefore thought to be sufficient to enable the invention to be fully understood.

Means are provided for forwarding a 85 blade to and holding it against the grinder during the grinding operation, and this means may vary within wide limits. As shown, a rotating turret 8 is used for this purpose. It is to be understood, of course, that there are two of these turrets. Each 90 of the turrets is fixed upon the upper end of a vertical shaft 9 journaled in a bearing 10 formed in the main frame 5, and also in a bearing 11 formed in a bracket 12 secured to the main frame 5. Upon the lower end of each shaft 9 is fixed a worm wheel 13 which is in mesh with a worm 14 carried by a horizontal shaft 15 which is the main power shaft of the machine. This shaft is provided with the usual fast and loose pulleys 16 and 17. By the mechanism just described, the two turrets are simultaneously rotated at the same speed and in the same direction, as indicated by the arrows 18.

The means for forwarding a blade to, or past, the grinder, includes a movable member and a stationary member. The turret just described constitutes the movable member. The stationary member consists in concave guides 19 mounted upon the frame 5 110

adjacent the periphery of the turrets, the concavity of the guides being concentric with the periphery of the turrets. The guides 19 are spaced from the periphery of the turrets a distance equal to the thickness of the blades to be operated upon. For the purpose of preventing any slipping of a blade placed between the periphery of the turrets and the guides at 20, each 5 of the turrets is provided with a plurality of sets of positioning pins 21, which are adapted to engage perforations in the blades, when perforated blades are to be operated upon. It is to be understood, however, that 10 15 when non-perforated blades are to be operated upon, other positioning means may be used in place of the pins.

For the purpose of enabling blades to be ground without danger of injury to the temper 20 of the steel of which they are made, means are provided for producing a flow of oil to the surface of the grinder, and this means may vary within wide limits. As shown, however, a reservoir 22 is provided, which contains oil of a suitable character. From this reservoir, a pipe 23 leads to a pump 24 of a well known type. Since 25 a detailed description of this pump is unnecessary to an understanding of the present invention, it is omitted in the interest of 30 clearness and brevity. The pump is driven by a belt 25 running over a pulley 26 on the shaft 15 before referred to, and also over a pulley 27 on the pump shaft. The pump 35 forces oil up through a pipe 28 to branch pipes 29 and 30 which terminate respectively in nozzles 31 and 32 adjacent the peripheral surfaces of the grinding wheels. A flow of oil is thus produced which prevents 40 overheating of blades during the grinding operation. The oil that flows from the nozzles 31 and 32 drops from the wheels to the flanged table of the frame 5 and flows through a drain pipe 41 into the reservoir 22, from which it is again pumped to the wheels.

For the purpose of finishing the edge of a blade passed through the machine, without rehandling, there is provided a polisher 50 or polishing wheel 33 operating upon the ground edge immediately after the grinding operation is completed. Each of the polishing wheels is mounted in a bracket 55 60 suitably positioned adjacent the periphery of the turrets 8.

Means are provided for adjusting the grinders and polishers toward or away from the forwarding means or turret to compensate for wear and to regulate the depth of 65 the cut taken from the side of the blade blank to form the cutting edge, and to regulate the degree of polish imparted to the ground edge. This means may vary within wide limits. As shown, however, the same 65 means is employed for adjusting each of the

grinders and each of the polishers; that is to say, means identical in structure is employed. The brackets 4 and 34 are arranged to be clamped upon the vertical arm 35 of a two arm lever 35, 36, by means of a clamp screw 37. The lever 35, 36 is pivoted at 38 to a support 39 secured to the frame 5 before referred to. An adjusting screw 40 is threaded through the horizontal arm 36 of the lever and contacts with the support. 70 By this mechanism, the grinders or polishers may be adjusted vertically and also toward or away from the forwarding means or turrets. 75

In the operation of the device, blades are 80 successively placed upon the pins 21 at 20 and guided between the periphery of the turrets and the cooperating stationary guides, after which the blades are automatically forwarded to and past the grinders 85 and polishers and back to a position at the front of the machine where they are taken from the pins.

Changes and variations may be made in the structure by means of which the invention is carried into effect. The invention, therefore, is not to be restricted to the precise details of the structure shown and described.

What is claimed is:—

1. In a machine for grinding razor blades, the combination with a grinding wheel, of a rotating turret provided with pins for engaging a perforated blade to forward it past the grinding wheel, and a concave stationary guide adjacent and concentric with the periphery of the turret. 95

2. In a machine for grinding razor blades, the combination with a guide having a curved channel adapted to support a normally flat blade temporarily bent to conform to the curvature of the channel, of a grinding wheel projecting into the channel, and means for forwarding a blade through the channel. 105

3. In a machine for grinding razor blades, the combination with a guide having a curved channel adapted to support a normally flat blade temporarily bent to conform to the curvature of the channel, said 115 channel being formed by a stationary member and a movable member, of a grinding wheel projecting into the channel, and means for moving the movable member to forward a blade through the channel. 110

4. In a machine for grinding razor blades, the combination with a guide having a curved channel adapted to support a normally flat blade temporarily bent to conform to the curvature of the channel, said 125 channel being formed by a stationary member and a movable member having a series of pins adapted to engage a perforation in a blade, of a grinding wheel projecting into the channel, and means for moving the mov- 130

- able member to forward a blade through the channel.
5. In a machine for grinding razor blades, the combination with a guide having a curved channel adapted to support a normally flat blade temporarily bent to conform to the curvature of the channel, said channel being formed by a stationary member and an endless movable member having a series of pins adapted to engage a perforation in a blade, of a grinding wheel projecting into the channel, and means for moving the movable member to forward a blade through the channel.
15. 6. In a machine for grinding razor blades, the combination with a guide having a curved channel adapted to support a normally flat blade temporarily bent to conform to the curvature of the channel, said channel being formed by a horizontal rotatory turret having a periphery unbroken except by a series of pins adapted to engage a perforation in a blade and by a horizontal stationary guide adjacent the periphery of the turret, of a grinding wheel projecting into the channel, and means for rotating the turret to forward a blade through the channel.
20. 7. In a machine for grinding razor blades, the combination with a guide having a curved channel adapted to support a normally flat blade temporarily bent to conform to the curvature of the channel, of a grinding wheel projecting into the channel, means for adjusting the wheel toward the channel, and means for forwarding a blade through the channel.
25. 8. In a machine for grinding razor blades, the combination with a guide having a curved channel adapted to support a normally flat blade temporarily bent to conform to the curvature of the channel, of a grinding wheel projecting into the channel, means for adjusting the wheel toward and away from the channel, means for adjusting the wheel transversely with respect to the channel, and means for forwarding a blade through the channel.
30. 9. In a machine for grinding razor blades, the combination with a guide having a curved channel adapted to support a normally flat blade temporarily bent to conform to the curvature of the channel, of a grinding wheel projecting into the channel and consisting of a plurality of separated disks adapted to operate upon a blade held against displacement by the curvature of the channel and the natural resiliency of the blade, and means for forwarding a blade through the channel.
35. 10. In a machine for grinding razor blades, the combination with a guide having a curved channel adapted to support a normally flat blade temporarily bent to conform to the curvature of the channel, of a grinding wheel projecting into the channel, means for adjusting the wheel toward the channel, and means for forwarding a blade through the channel.
40. 11. In a machine for grinding razor blades, the combination with a guide having a curved channel adapted to support a normally flat blade temporarily bent to conform to the curvature of the channel, of a grinding wheel projecting into the channel, means for adjusting the wheel toward and away from the channel, means for adjusting the wheel transversely with respect to the channel, and means for forwarding a blade through the channel.
45. 12. In a machine for grinding razor blades, the combination with a guide having a curved channel adapted to support a normally flat blade temporarily bent to conform to the curvature of the channel, of a grinding wheel projecting into the channel, a polishing wheel spaced from the grinding wheel and also projecting into the channel, said wheels being adapted to operate upon a blade held against displacement by the curvature of the channel and the natural resiliency of the blade, and means for adjusting the wheel toward and away from the channel, means for adjusting the wheel transversely with respect to the channel, and means for forwarding a blade through the channel.
50. 13. In a machine for grinding razor blades, the combination with a guide having a curved channel adapted to support a normally flat blade temporarily bent to conform to the curvature of the channel, of a grinding wheel projecting into the channel, a polishing wheel spaced from the grinding wheel and also projecting into the channel, said wheels being adapted to operate upon a blade held against displacement by the curvature of the channel and the natural resiliency of the blade, and means for adjusting the wheel toward and away from the channel, means for adjusting the wheel transversely with respect to the channel, and means for rotating the turret to forward blades through the channel.
55. 14. In a machine for grinding razor blades, the combination with a guide having a curved channel adapted to support a normally flat blade temporarily bent to conform to the curvature of the channel, of a grinding wheel projecting into the channel and consisting of a plurality of separated disks adapted to operate upon a blade held against displacement by the curvature of the channel and the natural resiliency of the blade, and means for forwarding a blade through the channel.
60. 15. In a machine for grinding razor blades, the combination with a guide having a curved channel adapted to support a normally flat blade temporarily bent to conform to the curvature of the channel, of a grinding wheel projecting into the channel, means for adjusting the wheel toward the channel, and means for forwarding a blade through the channel.
